UNITED STATES PATENT OFFICE.

ALFRED F. HARRIS, OF WARREN, OHIO, ASSIGNOR TO THE HARRIS AUTOMATIC PRESS COMPANY, OF NILES, OHIO, A CORPORATION OF OHIO.

DELIVERY MECHANISM.

1,337,223.

Specification of Letters Patent. Patented Apr. 20, 1920.

Application filed May 1, 1916. Serial No. 94,580.

To all whom it may concern:

Be it known that I, ALFRED F. HARRIS, a citizen of the United States, residing in Warren, in the county of Trumbull and State of Ohio, have invented certain new and useful Improvements in Delivery Mechanisms, of which the following is a specification, reference being made to the accompanying drawings, forming a part thereof.

This invention relates to certain improvements in delivery mechanisms which are used in connection with printing or like machines, for taking the sheets or stock from the press or machine and transferring same to a pile-receiving table which shall be automatically lowered to accommodate the growth of the pile of sheets.

The objects of my invention are, among other things, to provide an improved delivery mechanism whereby the sheets or stock are first taken from a cylinder of the printing machine or press and are carried with a gradually decreasing speed, whereby the sheets are released and deposited ultimately on the pile on the receiving table at a reduced speed, which is of great advantage in lessening the chance of injury to the stock or sheets. A further object of my invention is to provide an automatic guard device operatively connected by a clutch mechanism with the press feeder, which advances the separate sheets of stock to the press, so that by the throwing out of the feeder clutch by the tripping mechanism through the failure of any sheet in being properly presented to the impression-cylinder of the press, or, for any other reason when the feeder clutch is thrown out of operative contact, the delivery pile-lowering mechanism, connected with the stock-delivery mechanism and with the main part of the press, is automatically disconnected, thereby insuring that both the pile-feeding mechanism and the pile-delivery mechanism herein shown shall always work in unison.

With these and other objects in view, the invention comprises the constructions and operating parts forming the delivery mechanism herein shown and hereafter to be described as one embodiment of my invention, such other features being fully and specifically set forth in the claims.

The accompanying drawings show this embodiment of the invention in connection with an "off-set" printing press, the same

serving, in connection with a sheet-feeder, to fully explain the invention, which is not restricted, however, to any particular form or type of printing-press or sheet-feeder construction.

Referring to the accompanying drawings, Figure 1 is a side elevation of the sheet-delivery mechanism showing a portion of a cylinder-press;

Fig. 2 is an enlarged detailed side view of the operating mechanism for the delivery mechanism;

Fig. 3 is a diagrammatic side elevation of a cylinder-press and also a diagrammatic illustration of a portion of a sheet-feeder adapted to feed sheets to the cylinder-press;

Fig. 4 is an enlarged sectional end view of a form of clutch-operating mechanism for the sheet-feeder and sheet-delivery mechanism;

Fig. 5 is a plan view of the mechanism illustrated in Fig. 3;

Fig. 6 is an enlarged detail plan view of the sheet-slitting mechanism;

Fig. 7 is an enlarged detail view illustrating the operating mechanism for the sheet-receiving table of the delivery mechanism;

Figs. 8 and 9 are detail views of a form of sheet-grippers;

Figs. 10, 11 and 12 are diagrammatic views illustrating different arrangements of the sheet-conveying chains and grippers carried thereby.

Similar numerals refer to similar parts throughout the several figures.

Referring to Fig. 3, the frame 13 supports the bearings of the form-cylinder 14, the transfer-cylinder 15, and the impression-cylinder 16, said cylinders being mounted on the shafts 17, 18, and 19 respectively, which are journaled in the frame 13, as shown. The cylinders are so constructed and arranged in the frame 13 that the transfer-cylinder 15 forming a printing-couple with the impression-cylinder 16, receives its design from the form-cylinder 14. The form, transfer and impression cylinders have each fastened thereto suitable gears whose pitch-diameter coincides with the periphery of the respective cylinders. These gears (not shown) intermesh and form the driving mechanism to secure proper rotation for the respective cylinders, the impression-cylinder rotating in a contra-clockwise direction, as shown by the arrow in Fig. 3. 20 indicates the skele-

ton delivery cylinder, preferably constructed of a plurality of disks 21 of equal diameter with the impression-cylinder 16 mounted on the collars 22 secured to the shaft 23, as shown in Fig. 6, the shaft 23 being journaled in the frame 13, as shown in Fig. 3. The skeleton delivery cylinder 20 has a suitable gear secured thereto (not shown) which intermeshes with the gear on the impression-cylinder 16, the cylinders 16 and 20 being arranged to rotate at the same peripheral speed. The power is derived from any suitable source through the pulley 24 mounted on the pulley shaft 25, thence through the miter-gears 26 and 27, the gear 27 being mounted on the shaft 23 of the cylinder 20, as shown in Fig. 5. The delivery-cylinder 20 is driven in a clockwise direction, as shown by the arrow in Fig. 3, by this mechanism, and the intermeshing gears on the impression, transfer and form cylinders coact to secure the proper rotation of the respective cylinders. 28 designates a form of stock or sheet grippers (shown in Fig. 1) carried by the delivery cylinder 20, which are arranged to successively seize the individual sheets from the impression-cylinder 16 and carry same to the delivery mechanism proper. Since these are common forms of printing machinery construction and are well-known in the art, they need not be more fully shown or described.

Referring to Fig. 3, 29 indicates the frame of any suitable form of sheet-feeding device in which the upper feed roll 30 and the lower feed roll 31 are journaled as shown. Secured to the frame 29 and extending to the frame 13 is the feed table 32 having a plurality of feed rollers 33 journaled thereto to advance the individual sheets to the impression-cylinder 16. The lower feed roll 31 has mounted to its shaft the miter-gear 34 engaging with the miter-gear 35 secured to the vertical shaft 36 journaled to brackets 37 and 38, mounted in the frame 29. The lower end of the shaft 36 carries the miter-gear 39 engaging with the miter-gear 40 secured to the horizontal shaft 41 journaled in the bracket 42, mounted in the frame 29. The other end of the shaft 41 carries the positive clutch-member 43, adapted to engage with the clutch member 44 mounted on a shaft carrying the miter-gear 45 which engages with the miter-gear 46 mounted on the delivery-cylinder shaft 23, as shown in Fig. 5. When the clutch members 43 and 44 are in operative connection, the shafts 36 and 41 revolve in the directions shown by the arrows in Fig. 3, and the feed rolls 30 and 31 rotate to advance the individual sheets to the left along the feed-table 32 to be seized by the gripping devices (not shown) on the impression-cylinder 16, and thence through the press.

65 The tripping mechanism for the feeder

which automatically disconnects the feeder clutch device just described, comprises the following mechanism: Extending transversely above the feed-table 32 and journaled in upright supports on the sides 70 thereof, as shown in Fig. 4, is the shaft 47 which carries the arm 48 connected by the rod 49 to the shaft 23 of the delivery-cylinder 20. The lower end of the rod 49 is connected at 50 to the crank-plate 51 mounted 75 on one end of the shaft 23, which mechanism, through the rotation of the shaft 23, imparts to the shaft 47 an oscillating movement. 52, 52 indicate two grooved collars rigidly secured to the shaft 47. Adjacent 80 each grooved collar 52 is the disk 53 affixed to the end of the tubular shaft 54, which is loosely secured on, and incloses a portion of, the shaft 47, as shown in Fig. 4. The shaft 54 carries the arm 55, the outer end of 85 which engages with the arm 56 mounted on the block 57 secured to the shaft 58 mounted in the frame 13. 59 indicates the trip-lever pivoted at 60 between the parallel sides of the grooved collars 52, so that its longer and 90 heavier arm is held from falling into the aperture 61 cut in the top of the feed-table 32 by the interposition of the sheet or stock 62, as shown in Fig. 4. At the opposite end the lever 59 is T-shaped to form the tooth 95 63, and in the peripheries of the collars 52, and also in the periphery of the disk 53, are formed cut-outs 64 and 65 respectively. Ordinarily the tooth 63 rests against, or is in proximity to, the periphery of the disk 53; 100 it can engage with the cut-out 64 of the collars 52 only when the tooth can fall into the cut-out 65 of the disk 53. When this union occurs, the disk 53 with its shaft 54, which are normally at rest, are locked to, and turn 105 with, the oscillating shaft 47. The entrance of this tooth 63 into locking engagement with the disk 53 will occur upon the failure or interruption in the feeding of the stock over the table 32. When the sheets 62 are 110 in proper position, as shown in Fig. 4, the curved longer arm of the trip-lever 59 will engage therewith, and will be prevented from lowering in the aperture 61, and from turning sufficiently to interlock with the 115 disk 53, as shown in Fig. 3. If the stock or sheets 62 should, at any time, be interrupted or absent, the longer arm of the lever 59 will fall of its own weight into the aperture 61, thereby causing the tooth 63 to interlock 120 with the cut-out 65 in the disk 53. Thus the tubular shaft 54 will be caused to oscillate in unison with the shaft 47, causing the laterally projecting roller 55^a on the arm 55 to engage with the arm 56 mounted on the 125 block 57 to rock the shaft 58 in a clockwise direction, the operation of these parts being clearly shown in Figs. 3 and 4. Secured to the shaft 58 is the arm 66 connected by the link 67 to the rock-arm 68 secured to the 130

transverse shaft 69 journaled in the frame 13, as shown in Figs. 3 and 5. The arm 70 is secured to the shaft 69 and carries the roller 71 which engages in the annular groove 72 formed in the collar 73 affixed to the positive clutch-member 43, both of which are loosely sleeved about the shaft 41, as shown. When the lever 59 is tripped to cause an oscillating movement to the shaft 54, the arm 56 is moved to the left in Fig. 3, thereby giving an upward movement to the link 67, which then disconnects the clutch members 43 and 44 by a counter-clockwise movement of the arm 70. A hand-lever 74 10 may be secured to the shaft 69 to insure the disconnection of the clutch members at any desired moment, as shown in Fig. 3.

Through this herein described mechanism, the absence or failure of feed of the stock 20 while tripping the cylinders, also automatically disconnects the feeder from the press, permitting the former to remain idle with no stock being fed forwardly, while the press itself rotates. This separation becomes desirable when running the cylinders 25 and inking mechanism with the impression off, for example, in working up the ink on the rollers preparatory to printing.

Referring to Fig. 6, 75 and 76 indicate 30 two spaced-apart sprocket wheels mounted on the shaft 23, said wheels being of the same diameter as the disks 21 which constitute the skeleton delivery-cylinder 20.

Traveling beneath, and operated by, the 35 sprocket wheels 75 and 76 are two spaced-apart endless sprocket chains 77 and 78, which are arranged to move with the same peripheral speed as the periphery of the cylinder 20. These sprocket chains 77 and 40 78 pass around two smaller sprocket wheels 79 and 80 respectively, mounted on a transverse shaft 81 journaled in the frame 13, as shown in Figs. 3 and 5. The chains 77 and 78 travel in the direction of the arrows 45 shown in Fig. 1, first moving in a horizontal direction from the delivery-cylinder 20, and then moving vertically around idler wheels 82 and 83 mounted on the shafts 84 and 85 respectively, journaled in the frame 13, as 50 shown. The upper loops of these chains 77 and 78 pass around the sprocket wheels 86 (only one being shown in Fig. 1), secured to a transverse shaft 87 journaled in brackets 88 and 89 secured to the pile-delivery 55 frame 90, all as shown in Fig. 1. It will be understood that the two endless chains 77 and 78 are arranged at either side of the delivery-mechanism, and necessarily move simultaneously in the same directions and at 60 the same speeds with each other to carry the successive sheets from the cylinder 20, as will be understood by those familiar with printing machinery construction.

These chains 77 and 78 carry means for 65 transferring the sheets or stock from the

delivery-cylinder 20, and such means are arranged in the present embodiment to travel with the pitch line of the chains and therefore at the same speed at all times, and also with the same speed as that of the peripheries of the disks 21. In the present embodiment, the stock-engaging means or sheet grippers are shown in detail in Figs. 8 and 9. The particular structure of such grippers may be widely varied. Referring 70 to Figs. 8 and 9, the grippers comprise a rock-shaft 91 carrying grippers 92 which are normally held in engagement with the collars 93 keyed on a rod 94, held in close parallelism with the shaft 91. The shaft 91 80 and the rod 94 travel in a different plane from that of the chains 77 and 78 and are mounted thereon so as to be held either inwardly or outwardly disposed from the carrier chains, as shown in Fig. 1. The device 85 to accomplish this relationship comprises the frame 95 securely affixed to the chains 77 and 78. The grippers 92 are normally held in engagement with the collars 93 by a spring 96 attached to and wound around the 90 shaft 91 and fastened to the frame 95. At one end, each shaft gripper shaft 91 carries an arm 97 bearing on its outer end a frictional roller 98 which, upon engagement with suitably located cams or other devices, 95 located on the apparatus, will effect the opening of the grippers 92 at the proper times and in predetermined positions.

Referring to Figs. 1, 5 and 7, the pile-delivery frame 90 comprises two vertical members 99 and 100 (Fig. 7) spaced-apart sufficiently to accommodate the width of the stock or sheets, and two equally spaced-apart horizontal members 101 and 102 (Fig. 5) supported on standards 103 (only one being shown in Fig. 1). 104 and 105 indicate two sets of endless chains horizontally disposed, and revolving at one end about the sprocket wheels 106 and 107 mounted on a common shaft 108 journaled in the members 100 101 and 102, as shown in Fig. 5. At the other ends of horizontal members 101 and 102, the chains 104 and 105 pass around the sprocket wheels 109 (only one being shown) mounted on a common shaft 110 journaled 110 in the members 101 and 102. These chains travel in the direction shown by the arrows 115 in Fig. 1, and are driven by the sprocket chain 111 which passes around the sprocket gear 112 mounted on the shaft 87, and thence 120 around the sprocket gear 113 mounted on the shaft 108, the size of these gears and sprocket wheels 106, 107 and 109 being such that the chains 104 and 105 travel at about two-thirds the speed of the chains 77 and 78. 125 The sheet grippers heretofore described and shown in detail in Figs. 8 and 9 are elevated above the pitch line of the chains 104 and 105, as shown in Fig. 1, and take the successive sheets from the chains 77 and 78 just 130

before completing their travel around the sprocket wheels 106 and 107, and while traveling at an increased speed, due to their elevated circular orbit, which is equal to the speed of travel of the chains 77 and 78. Immediately after the grippers seize the sheet, they move to the left in Fig. 1 in a straight horizontal direction across the top of the pile, which reduces the speed of travel of the sheet about one-third. The sheet is then released and dropped on the pile at this reduced speed, which is a decided advantage in lessening the chances of injury to the leading edges of the successive sheets. It is apparent that the speed of the successive sheets may be further reduced step by step by other sets of chains traveling at gradually diminishing speeds, as may be found desirable in view of the character of the stock which is being delivered.

The pile-delivery table 114, upon which the stock or sheets are stacked, is shown suspended by supporting chains 115 and 116, which pass over idler wheels 117 and 118, and are then wound around the sprocket wheels 119 and 120 secured on the shafts 121 and 122 respectively, journaled in the vertical members 99 and 100, as shown in Fig. 7. Between the two members 99 and 100, is journaled the transverse shaft 123 carrying two single-thread worms 124 and 125, being left-hand and right-hand threads respectively, as shown in Fig. 7. The worms 124 and 125 engage the worm-gears 126 and 127, mounted on the shafts 121 and 122. One end of the shaft 123 is squared to receive the removable hand-crank 128 which is shown in dotted lines in Fig. 7.

The means for automatically lowering the table 114 to compensate for the gradual growth of the pile of sheets upon such table comprises the following mechanism; journaled in the bracket 88 is shaft 129 which carries the gear 130 engaging with the gear 131 secured to the shaft 87, the size of the respective gears being such that the shaft 129 makes one revolution to each revolution of the impression-cylinder 16. Mounted on the shaft 129 is the cam 132 which engages the outer end of the rock-arm 133 pivoted on a stud in the bracket 88, the rock-arm being held in engagement with the cam 132 by a spring (not shown) coiled around the stud. The outer end of the arm 133 is connected by the link 134 to the rock-arm 135, which carries the rod 136 pivotally secured to the outer end of the rock-lever 137 loosely mounted on the shaft 123 as shown in Fig. 1. Referring to Fig. 2, the inner end of the lever 137 carries the pivoted pawl 138 which engages the ratchet 139 keyed to the shaft 123. The spring 140 holds the pawl 138 in engagement with the teeth of the ratchet 139. The oscillation of the lever 137 by the rotation of the cam 132 with each revolution

of the press cylinders, gives a step-by-step rotation to the worms 124 and 125, thereby lowering the pile-receiving table 114 slightly to accommodate for the growth of the pile thereon.

To eliminate the necessity for a governor for controlling the height of the pile, a cam-shaped regulating disk 141 is provided, which is loosely mounted on the shaft 123. This disk is adjustable about the shaft by the spring latch-pin 142 mounted in the vertical member 99, as shown in Fig. 2, the pin 142 engaging with suitably formed teeth 143 cut in the periphery of the disk 141. The handle 144 enables the operator to make this adjustment to suit the thickness of the stock; the opposite end is beveled at 145 to adjustably coöperate with the pin 146 affixed to the pawl 138, thereby to control the number of teeth in the ratchet 139 to be advanced at each reciprocation of this pawl, which is carried by the oscillating rock-lever 137 which is operated as hereinbefore described.

Referring to Figs. 1, 2 and 3, I have provided automatic means to wholly disengage the pawl 138 from the ratchet 139 which becomes operable when the clutch members 43 and 44 become disconnected by the failure or absence of stock being fed to the press as heretofore explained, or, when for any reason it is desired to rotate the press mechanism without having stock being fed thereto, in which case the pile-delivery mechanism should also cease its operation. Secured to the transverse shaft 69 is the arm 147 connected by the link 148 to the rock-arm 149 mounted on the end of the horizontally-disposed shaft 150 journaled in the brackets 151 and 152 secured to the frame 13. The opposite end of the shaft 150 carries the rock-arm 153 connected by the rod 154 to the bell-crank lever 155 journaled to the rock-shaft 156 secured in the vertical member 99. The upper arm or guard 157 of the lever 155 is adapted to engage the pin 146 on the pawl 138, as shown in Fig. 7. When the feeder is tripped, and the clutch members 43 and 44 are separated, the above described mechanism simultaneously and automatically pulls the guard arm 157 to the left in Fig. 2, thereby striking the pin 146 and lifting the pawl 138 out of engagement with the ratchet 139 which disconnects the table-lowering mechanism heretofore described, until such time the trip and clutch members 43 and 44 are restored to operative position. If this automatic device were not employed, the pile-delivery mechanism would operate with the main part of the press, although no sheets or stock were being delivered through such press and mechanism. To prevent this, the above described automatic device is utilized so that the throwing out of the feeder clutch members instantly gives a partial rotation to the shaft 150 which in turn raises

the guard arm 157 and separates the oscillating pawl 138 from its coöperating ratchet 139, as has just been described, to disconnect the pile-lowering mechanism.

5 Referring to the diagrammatic illustrations shown in Figs. 10, 11, and 12, I have here shown variations in the sheet-delivery chain mechanism involving the different sets of carrier chains with their stock-engaging 10 grippers to take the sheets from the delivery-cylinder 20 and transfer them at reduced speeds to the pile-receiving table 114.

In Fig. 10, the pitch line of the two sets of chains is designated by the numerals 15 170 and 171 respectively, and the grippers in the first set 170 travel in a depressed line, as shown by the inner line in Fig. 10, while the grippers of the second set 171 travel in an elevated line, as shown by the 20 outer line; the speed of the second set of chains, horizontally disposed, is less than that of the first set, but as the chains meet at the point 172 the grippers of the respective sets will be traveling at the same speed 25 to properly transfer the sheets from the first set to the second set of carrier chains.

In Fig. 11, I have shown a further variation in the use of two-obliquely-disposed sprocket wheels 173 and 174 to form the 30 upper loop of the first set of chains. Between the wheels 173 and 174 a fixed curved shoe 175 is secured around which the first chain is compelled to travel between the sprocket wheels 173 and 174. This gives a 35 reverse curve to the path of the chains which causes the grippers, which are traveling in the elevated line marked 176, to travel more slowly than the chain itself, while transferring the sheet to the second set of horizontally-disposed chains at, or adjacent to, the shoe 175, the grippers in the second set 40 traveling in the elevated line, as shown at the transfer.

In Fig. 12, I have shown another variation 45 which is similar to that illustrated in Fig. 10, except that an idler sprocket wheel 177 is interposed between the two main sprocket wheels for the second set of chains, which sprocket 177 produces a curve in the 50 path of the chain moving in the direction of the arrow. The grippers in the first set of chains 170 travel in depressed lines, while the grippers in the second set 171 travel in the elevated line. As the chain passes over 55 the sprocket 177, the grippers are brought more or less to a standstill; and the conveyed sheet or stock ceases its travel to the left during that moment when the carrier chains are passing over this sprocket wheel 60 177 when such sheet or stock is then being released to drop on the table 114.

The operation of the hereinbefore described delivery-mechanism is substantially as follows:—When the clutch members 43 65 and 44 are in operative contact, all the cylin-

ders, constituting the press, are rotated by power derived from the pulley 24, also the sheet-feeder, diagrammatically shown in Fig. 3, in which the feed rollers 30 and 31 successively advance the sheets or stock over 70 the table 32 to be engaged by the grippers on the impression-cylinder 16 to successively print said sheets or stock in the printing couple formed by the cylinders 15 and 16, and thence deliver the sheets to the grippers 75 28 on the delivery-cylinder 20, the cylinders 16 and 20 rotating in the direction of the arrows shown in Fig. 3. As the sheets successively pass in a clockwise direction on the cylinder 20, they are held under positive 80 control by the grippers 28 heretofore described. The sheets then pass to the stock-engaging grippers on the chains 77 and 78 which are traveling at the face speed of the periphery of the delivery cylinder 20, 85 and are thence carried first horizontally and then vertically, as shown in Fig. 1, until the chains 77 and 78 curve about the sprocket wheels 86 on the shaft 87, when the stock-engaging grippers, secured to the horizontally-disposed chains 104 and 105 which 90 rotate at a reduced speed compared with the chains 77 and 78, carry same to the left, as shown in Fig. 1, preferably at two-thirds such speed. As the chains 104 and 105 pass 95 around the sprocket wheels 106 and 107, the grippers, being elevated, move at the same speed as the pitch line of the chains 77 and 78, the grippers on the chains 77 and 78 being so positioned that they receive and 100 release the sheet on the pitch line of the chains 77 and 78. As the grippers meet, as shown in Fig. 1, the grippers on the first set of chains release the sheet to be seized by the grippers secured to the chains 104 and 105, and as soon as the chains 104 and 105 travel toward the left in Fig. 1, their speed is reduced one-third. At a predetermined point, after the sheet is transferred 105 to a vertical position over the pile-receiving 110 table 114, the grippers open and allow the successive sheets to drop on this table.

The grippers may travel in the pitch line of the chains, or may extend inwardly or outwardly, so long as they deliver the leading edges of the successive sheets at the same speed at the point of transfer from the first set of chains to the second set of chains, such variations in the sizes of the sprockets and the formation and position of the grippers 115 on the chains being accommodated to accomplish the result of a gradual reduction of speed in the successive changes of carrier chains in the delivery-mechanism, whereby the sheets are deposited on the table 120 114 without injuring same.

While the sheets are being successively delivered to the table 114 through the operation of the mechanism just described, such table 114 is gradually lowered to accommo- 130

date the growing height of the pile thereon through the lengthening of the supporting chains 115 and 116, which gradually unwind around the sprocket wheels 119 and 120 through the step-by-step rotation of the transverse shaft 123, brought about by the oscillating rock-lever 137 carrying the pawl 138 which operates one or more teeth of the ratchet 139, thereby imparting a slight rotation to the sprocket wheels 119 and 120 to lower the table 114 at each revolution of the press, since the rock-lever 137 makes a single reciprocation with each revolution of the impression-cylinder, as has been heretofore described. The friction of the worms 124 and 125, co-acting respectively with the worm gears 126 and 127, is usually sufficient to hold the pile-receiving table against lowering movement, except when actuated by the ratchet and pawl mechanism just described, although a light brake may be added if desired. After the accumulated pile has been removed from the table 114, it may be raised to its elevated position by means of the hand-crank 128, the pawl 138 having been theretofore disengaged from the ratchet 139, the shaft 123 being rotated through the crank 128 in a reverse direction, thereby to raise the table 114. The hand-crank 128 is removable and is left off the shaft 123, except when in use to actually raise the table 114.

Under normal conditions, the press cylinders are so arranged that if a sheet is not presented to the impression-cylinder 16, the automatic throw-off, shown more particularly in Fig. 4, trips the cylinders, and at the same time stops the entire press. At times, however, it is advantageous to run the cylinders and inking mechanism with the impression off, for example, in working up the ink on the inking rollers, as has been heretofore described. At such times the feeder should be disconnected and the automatic guard feature, which is one of the objects of my invention, is used to discontinue the operation of the pile-lowering mechanism when no sheets are being fed to the press. When the feeder clutches 43 and 44 are disconnected for any reason through the failure of feed of stock to the impression-cylinder, or a positive disconnection is made by the raising of the hand-lever 74, the link 148 is vertically elevated, which gives a partial rotation to the shaft 150, which, through the arm 153 and rod 154, rocks the bell-crank lever 155, so that the guard arm 157 wholly disconnects the pawl 138 from the ratchet 139, which allows the rock-lever 137 to oscillate without in any way operating the pile-lowering mechanism just described. This automatic disconnection therefore simultaneously stops the feeder and disconnects the pile-lowering mechanism to the end that both feeder and pile-lowering mecha-

nism shall always work in unison, while the manual controlling of the number of teeth which the pawl 138 shall engage on the ratchet 139, through the regulating disk 141, enables my delivery-mechanism to dispense 70 with a governor or other means for controlling the height of the pile on the table 114.

As heretofore explained, the diagrammatic constructions shown in Figs. 10, 11 and 12 illustrate several variations of the 75 disposition to be made between the different sets of carrier chains traveling at different speeds with their respective stock-engaging grippers disposed so that at the point of transfer between the two sets, the speeds of 80 the grippers shall be the same, to secure a true and even movement of the respective grippers at the point of transfer of the sheets from one set to the succeeding set.

While the construction described embodies 85 the invention in its preferred form, it will be understood that changes and variations may be made therein without departing from the invention.

It is to be further understood that while 90 constructions embodying the invention are particularly adapted for use in connection with printing machines they may be employed in other relations.

I claim as my invention:

1. In a delivery mechanism, the combination with an endless, flexible carrier having a loop-path and moving at a constant speed, of a second endless, flexible carrier having a loop-path and moving at a different constant speed, stock-engaging means mounted on each of said carriers, and means for causing the stock-engaging means on one carrier to momentarily travel at the same speed as the stock-engaging means on the other carrier, while transferring the stock from one carrier to the other carrier without changing the speed of the carriers. 95 100 105

2. In a delivery mechanism, the combination with an endless, flexible carrier having a loop-path and moving at a constant speed, of a second endless, flexible carrier having a loop-path and moving at a different constant speed, stock-engaging means mounted on each of said carriers, and means for changing the speed of one of said stock-engaging means, while transferring the stock from one carrier to the other carrier without changing the speed of either carrier. 110 115

3. In a delivery mechanism, the combination with an endless, flexible carrier having a loop-path and moving at a constant speed, of a second endless, flexible carrier having a loop-path and moving at a different constant speed, stock-engaging means mounted on each of said carriers, and means for changing the speed of one of said stock-engaging means, while transferring the stock from one carrier to the other carrier without changing the speed of either carrier. 120 125 130

4. In a delivery mechanism, the combination with a plurality of endless, flexible carriers each having a loop-path, each traveling at different relative speeds, of a like plurality of stock-engaging means mounted on each of said carriers, and means for temporarily equalizing the speed of travel of a stock-engaging means on one carrier with a stock-engaging means of another carrier, while transferring the stock from one carrier to the other carrier. 10

5. In a delivery mechanism, the combination with a plurality of endless, flexible carriers each having a loop-path, one of which travels at a different relative speed, stock-engaging means mounted on each carrier, and means for temporarily equalizing the speed of travel of the stock-engaging means on each carrier with the stock-engaging means on another carrier while transferring the stock from one carrier to another carrier. 15

6. In a delivery mechanism, the combination with a plurality of endless, flexible carriers each having a loop-path, one of which travels at a different relative speed, stock-engaging means mounted on each carrier, and means for temporarily equalizing the speed of travel of the stock-engaging means on each carrier with the stock-engaging means on another carrier while transferring the stock from one carrier to another carrier without changing the relative speeds of said carriers. 25

7. In a delivery mechanism, the combination with a cylinder of a printing or like machine, of an endless, flexible carrier having a loop-path and moving at a constant speed, a second endless flexible carrier having a loop-path and moving at a different constant speed, stock-engaging means mounted on each of said carriers, and means for causing the stock-engaging means on one carrier to momentarily travel at the same speed as the stock-engaging means on the other carrier, while transferring the stock from one carrier to the other carrier without changing the speed of the carriers. 35

8. In a delivery mechanism, the combination with a cylinder of a printing or like machine, of an endless, flexible carrier having a loop-path and moving at a constant speed, a second endless flexible carrier having a loop-path and moving at a different constant speed, stock-engaging means mounted on each of said carriers, and means for changing the speed of one of said stock-engaging means, while transferring the stock from one carrier to the other carrier without changing the speed of either carrier. 55

9. In a delivery mechanism, the combination with a cylinder of a printing or like machine, of an endless, flexible carrier having a loop-path and moving at a constant speed, a second endless, flexible carrier having a loop-path and moving at a different constant speed, 65

speed, stock-engaging means mounted on each of said carriers, and means for changing the speed of one of said stock-engaging means, while transferring the stock from one carrier to the other carrier without changing the speed of either carrier. 70

10. In a delivery mechanism, the combination with a cylinder of a printing or like machine, of a plurality of endless, flexible carriers each having a loop-path, each traveling at different relative speeds, of a like plurality of stock-engaging means mounted on each of said carriers, and means for temporarily equalizing the speed of travel of a stock-engaging means on one carrier with a stock-engaging means of another carrier, while transferring the stock from one carrier to the other carrier. 75

11. In a delivery mechanism, the combination with a cylinder of a printing or like machine, of a plurality of endless, flexible carriers each having a loop-path, one of which travels at a different relative speed, stock-engaging means mounted on each carrier, and means for temporarily equalizing the speed of travel of the stock-engaging means on each carrier with the stock-engaging means on another carrier, while transferring the stock from one carrier to another carrier. 85

12. In a delivery mechanism, the combination with a cylinder of a printing or like machine, of a plurality of endless, flexible carriers each having a loop-path, one of which travels at a different relative speed, stock-engaging means mounted on each carrier, and means for temporarily equalizing the speed of travel of the stock-engaging means on each carrier with the stock-engaging means on another carrier, while transferring the stock from one carrier to another carrier without changing the relative speeds of said carriers. 100

13. In a delivery mechanism, the combination with an endless, flexible carrier having a loop-path and moving at a constant speed, of a second endless, flexible carrier having a loop-path and moving at a different constant speed, stock-engaging means mounted on each of said carriers, means for causing the stock-engaging means on one carrier to momentarily travel at the same speed as the stock-engaging means on the other carrier, while transferring the stock from one carrier to the other carrier, and means for reducing the speed of the stock-engaging means on the other carrier before releasing said stock. 110

14. In a delivery mechanism, the combination with an endless, flexible carrier having a loop-path and moving at a constant speed, of a second endless, flexible carrier having a loop-path and moving at a different constant speed, stock-engaging means mounted on each of said carriers, means for changing the 125

speed of one of said stock-engaging means, while transferring the stock from one carrier to the other carrier without changing the speed of either carrier, and means for 5 reducing the speed of the stock engaging means on the second carrier before releasing said stock.

15. In a delivery mechanism, the combination with an endless, flexible carrier having 10 a loop-path and moving at a constant speed, of a second endless, flexible carrier having a loop-path and moving at a different constant speed, stock-engaging means mounted on each of said carriers, means for changing 15 the speed of one of said stock-engaging means, while transferring the stock from one carrier to the other carrier without changing the speed of either carrier, and means for reducing the speed of the stock-engaging 20 means on the other carrier before releasing said stock.

16. In a delivery mechanism, the combination with a plurality of endless, flexible carriers, each having a loop-path each traveling 25 at different relative speeds, of a like plurality of stock-engaging means mounted on each of said carriers, means for temporarily equalizing the speed of travel of a stock-engaging means on one carrier with a stock-engaging 30 means of another carrier, while transferring the stock from one carrier to the other carrier, and means for reducing the speed of the stock-engaging means on the other carrier before releasing said stock.

35. 17. In a delivery mechanism, the combination with a plurality of endless, flexible carriers each having a loop-path one or more of which travel at different relative speeds, stock-engaging means mounted on each carrier, means for temporarily equalizing the 40 speed of travel of the stock-engaging means on each carrier with the stock-engaging means on another carrier, while transferring the stock from one carrier to another carrier, 45 and means for reducing the speed of the stock-engaging means on the other carrier before releasing said stock.

18. In a delivery mechanism, the combination with a plurality of endless, flexible carriers each having a loop-path one or more of which travel at different relative speeds, stock-engaging means mounted on each carrier, means for temporarily equalizing the 50 speed of travel of the stock-engaging means on one carrier with the stock-engaging means on another carrier, while transferring the stock from one carrier to another carrier without changing the relative speeds of said carriers, and means for reducing the speed 55 of the stock-engaging means on the other carrier before releasing said stock.

60. 19. In a delivery mechanism, the combination with a cylinder of a printing or like machine, of a constantly moving endless, flexible carrier having a loop-path and traveling

at the face speed of said cylinder, stock-engaging means mounted thereon to take stock directly from said cylinder, a second constantly moving endless, flexible carrier having a loop-path and coöperating with, and traveling at a speed less than, said first carrier, stock-engaging means mounted thereon to travel, while transferring the stock from said first carrier, at the same speed as the first carrier, and means for releasing the stock 75 from said second carrier when traveling at its normal reduced speed.

20. In a delivery mechanism, the combination with a cylinder of a printing or like machine, of a constantly-moving endless, flexible carrier having a loop-path and traveling at the face speed of said cylinder, a plurality of stock-engaging means mounted thereon to take stock directly from said cylinder, a second constantly-moving endless, flexible carrier, having a loop-path and coöperating with and traveling at a speed less than, said first carrier, a plurality of stock-engaging means mounted thereon to travel, while transferring the stock from said first carrier, at the same speed as the first carrier, and means for releasing the stock from said second carrier when traveling at its normal reduced speed. 80

21. In a delivery mechanism, the combination with a delivery-cylinder of a printing 95 or like machine, of a constantly-moving endless, flexible carrier having a loop-path and traveling at the face speed of said cylinder, stock-engaging means mounted thereon to take stock directly from said cylinder, a second constantly-moving carrier coöperating with, and traveling at a speed less than, said first endless, flexible carrier having a loop-path and stock-engaging means mounted thereon to travel, while transferring the 100 stock from said first carrier, at the same speed as the first carrier, and means for releasing the stock from said second carrier when traveling at its normal reduced speed.

22. In a delivery mechanism, the combination with a delivery-cylinder of a printing 110 or like machine, of a constantly-moving endless, flexible carrier having a loop-path and traveling at the face speed of said cylinder, a plurality of stock-engaging means mounted 115 thereon to take stock directly from said cylinder, a second constantly-moving endless, flexible carrier having a loop-path and coöperating with, and traveling at a speed less than, said first carrier, a plurality of stock-engaging means mounted thereon to travel, while transferring the stock from said first carrier, at the same speed as the first carrier, and means for releasing the stock from 120 said second carrier when traveling at its normal reduced speed.

23. In a delivery mechanism, the combination with a cylinder of a printing or like machine, of a constantly-moving endless, flexible carrier having a loop-path and trav- 130

eling at the face speed of said cylinder, stock-engaging means mounted thereon to take stock directly from said cylinder, and traveling in the pitch line of said carrier, a second constantly-moving endless, flexible carrier having a loop-path and coöperating with, and traveling at a speed less than, said first carrier, stock-engaging means mounted thereon to travel, while transferring the stock from said first carrier, at the same speed as the first carrier, and means for releasing the stock from said second carrier when traveling at its normal reduced speed.

24. In a delivery mechanism, the combination with a cylinder of a printing or like machine, of a constantly-moving endless, flexible carrier having a loop-path and traveling at the face speed of said cylinder, a plurality of stock-engaging means mounted thereon to take stock directly from said cylinder, and traveling in the pitch line of said carrier, a second constantly-moving endless, flexible carrier having a loop-path and coöperating with, and traveling at a speed less than, said first carrier, a plurality of stock-engaging means mounted thereon to travel, while transferring the stock from said first carrier, at the same speed as the first carrier, and means for releasing the stock from said second carrier when traveling at its normal reduced speed.

25. In a delivery mechanism, the combination with a delivery-cylinder of a printing or like machine, of a constantly-moving endless, flexible carrier having a loop-path and traveling at the face speed of said cylinder, stock-engaging means mounted thereon to take stock directly from said cylinder, and traveling in the pitch line of said carrier, a second constantly-moving endless, flexible carrier having a loop-path and coöperating with, and traveling at a speed less than, said first carrier, stock-engaging means mounted thereon to travel, while transferring the stock from said first carrier, at the same speed as the first carrier, and means for releasing the stock from said second carrier when traveling at its normal reduced speed.

26. In a delivery mechanism, the combination with a delivery-cylinder of a printing or like machine, of a constantly-moving endless, flexible carrier having a loop-path and traveling at the face speed of said cylinder, a plurality of stock-engaging means mounted thereon to take stock directly from said cylinder, and traveling in the pitch line of said carrier, a second constantly-moving endless, flexible carrier having a loop-path and coöperating with, and traveling at a speed less than, said first carrier, a plurality of stock-engaging means mounted thereon to travel, while transferring the stock from said first carrier, at the same speed as the first carrier, and means for releasing the stock from said second carrier when traveling at its normal reduced speed.

for releasing the sheet from said second carrier when traveling at its normal reduced speed.

27. In a delivery mechanism, the combination with a cylinder of a printing or like machine, of a constantly-moving endless, flexible carrier having a loop-path and traveling at the face speed of said cylinder, stock-engaging means mounted thereon to take stock directly from said cylinder, a second constantly-moving endless, flexible carrier having a loop-path and coöperating with, and traveling at a speed less than, said first carrier, stock-engaging means mounted thereon, means for accelerating the speed of travel of said stock-engaging means on the second carrier to that of said first carrier, while transferring the stock from said first carrier, and means for reducing the speed of the stock-engaging means on said second carrier before releasing the stock.

28. The combination with a printing or like machine, of a sheet-feeding device to advance successive sheets to said machine, a sheet-delivery mechanism to carry the sheets to a pile-receiving table, both sheet-feeding and delivery mechanisms being actuated by said machine, means, operable by the delivery mechanism, for automatically lowering said table as the sheets accumulate thereon, means for disconnecting said sheet-feeding device, and means actuated by said last-mentioned means to stop said table-lowering means.

29. The combination with a printing or like machine, of a sheet-feeding device to advance successive sheets to said machine, a sheet-delivery mechanism to carry the sheets to a pile-receiving table, both sheet-feeding and delivery mechanisms being actuated by said machine, means, operable by the delivery mechanism, for automatically lowering said table as the sheets accumulate thereon, means for simultaneously disconnecting said sheet-feeding device and means actuated by said last-mentioned means to simultaneously stop said table-lowering means.

30. The combination with a printing or like machine, of a sheet-feeding device to advance successive sheets to said machine, a sheet-delivery mechanism to carry the sheets to a pile-receiving table, both sheet-feeding and delivery mechanism being actuated by said machine, means, operable by the delivery mechanism, for automatically lowering said table as the sheets accumulate thereon, means, controlled by the failure of the sheet feed, for disconnecting said sheet-feeding device and means actuated by said last-mentioned means to stop said table-lowering means.

31. The combination with a printing or like machine, of a sheet-feeding device to advance successive sheets to said machine, a sheet delivery mechanism to carry the
